UNITED STATES PATENT OFFICE.

EDWARD HUGO BOOS, OF MISSOULA, MONTANA.

TYPE-COMPOSING APPARATUS.

1,252,083.

Specification of Letters Patent.

Patented Jan. 1, 1918.

Application filed May 18, 1917. Serial No. 169,412.

To all whom it may concern:

Be it known that I, EDWARD H. BOOS, a citizen of the United States, and a resident of Missoula, in the county of Missoula and State of Montana, have invented a new and Improved Type-Composing Apparatus, of which the following is a full, clear, and exact description.

Among the principal objects which the present invention has in view are: to increase the speed and simplify the method of composing type for use in multigraphs and similar printing machines; to pre-arrange the composed matter before delivering it to the printing machine; to amplify the usefulness of printing machines of the character mentioned; to facilitate the justification of the printed matter prior to delivery thereof to the printing machine; and to review the composed matter and proof thereof prior to placing in position to print.

Drawings.

Figure 1 is a perspective view of a composing stick constructed and arranged in accordance with the present invention;

Fig. 2 is a perspective view showing a fragment of the above-mentioned stick and transfer means for removing type therefrom;

Fig. 3 is a cross section on an enlarged scale, the section being taken as on the line 3—3 in Fig. 1;

Fig. 4 is a detail view on an enlarged scale of the line gage employed in connection with the present invention;

Fig. 5 is a cross section on an enlarged scale of the transfer tube, the section being taken as on the line 5—5 in Fig. 2.

Description.

As seen in the drawings, a composing stick plate 15 is provided with a series of rectangular grooves 16, a calibrated scale 17, and a holding rack 18. The scale 17 is divided into spaces corresponding with the units of measure known in printing as non-parcels and picas. The scale 17 and holding rack 18 are employed for setting the gage blade 21. The blade 21 is provided to set the margin at the left of the printed column. The opposite margin is regulated by a closure plate 22 with which the stick plate 15 is provided.

The blade 21 is held in set position by the latch blades 23. The latch blades 23 have

each a shank 24 mounted on a pressure plate 25, which extends beyond the bottom of the body blocks 26. Each block 26 has an upturned flange 27 that extends between the body of the rack 18 and the adjacent edge of the stick plate 15. Each of the shanks 24 has a reduced section. Enfolding each reduced section is a spring 28. The spring 28 is arranged to normally press the blades 23 to engage the teeth of the rack 18.

The teeth of the rack 18 are arranged with reference to the markings on the scale 17, so that the forward edge of the blade 21 and of the lugs 29 dependent therefrom register with the various markings on the scale 17. The blade 21 and block 26 are held firmly in adjusted position by a screw 30.

The type used in multigraphs and machines of similar character have each a base 19, a neck 31 and a head 32. The heads 32 pass freely into the slots 16 of the plate 15. The surface openings in the grooves 33 in the multigraph cylinder 34 equal the width of the neck 31. When the type are placed on the cylinder and in the grooves 33 thereof, they are introduced into said grooves from the ends thereof. The neck 31 and head 32 closely fit the grooves 33 to be held immovable during the printing.

From the foregoing it will be understood that during the composing, the type are introduced into the grooves 16 without being entered from the ends thereof. This enables spacing members or slugs to be inserted in proper location for justification of the lines of the composition.

When one or more lines are composed, the type in the stick 15 are transferred to the grooves 33 in the cylinder 34 by a transfer rod 35. The rod 35 is a split tube, the cap or opening 36 whereof corresponds to the width of the neck 31 of the type.

The stick 15 has at one end thereof a series of cylindrical recesses 37 alined with the grooves 16 and corresponding in dimension with the rod 35 so that the end thereof may be snugly disposed in either of said grooves.

When composing lines of type which are to be transferred from the stick 15 to a cylinder, the blade 21 is removed from the stick block. This is accomplished by the operator lifting the pressure plate 25 until the blades 23 release the teeth of the rack 18. The blade 21 and parts connected therewith are then retracted toward the open end of the slots to be removed from the stick 15. The

end of the rod 35 is now introduced into one of the recesses 37 and the line of type in the groove 16 corresponding with that recess is then moved back through the groove 16 and into the tubular rod 35. The necks 31 of the various type pass between the gap edges of the rod 35 while the heads 32 of the said type extend within the hollow of the said rod. A spring clip 38 is mounted on the rod 35 to prevent the accidental passage of the type from the rear end of the rod 35.

Claims.

1. An apparatus as characterized comprising a stick plate having a series of parallel rectangular top-opening, type-holding grooves, said grooves having an entrance guide terminal recess; and means for determining the length of lines of composite type.
2. An apparatus as characterized comprising a stick plate having a series of parallel rectangular top-opening, type-holding grooves, said grooves each having an entrance guide terminal recess, said recess being substantially cylindrical to guide a type-transferring member deposited therein; and means for determining the length of lines of composite type.
3. An apparatus as characterized comprising a stick plate having a series of parallel rectangular top-opening, type-holding grooves, said grooves having an entrance guide terminal recess; and means for determining the length of lines of composite type, said means embodying a gage blade, and a clamp mounted in said blade for gripping the plate to hold said blade rigid thereon.
4. An apparatus as characterized comprising a stick plate having a series of parallel rectangular top-opening, type-holding grooves, said grooves having an entrance guide terminal recess; means for determining the length of lines of composite type, said means embodying a gage blade, and a clamp mounted in said blade for gripping the plate to hold said blade rigid thereon; and means for determining the position of said blade, said means embodying a rack bar rigidly mounted on said blade, and a spring-actuated latch member adapted for normally engaging the teeth of said rack bar.
5. An apparatus as characterized comprising a stick plate having a series of parallel rectangular top-opening, type-holding grooves, said grooves having an entrance guide terminal recess; means for determining the length of lines of composite type, said means embodying a gage blade, and a clamp mounted in said blade for gripping the plate to hold said blade rigid thereon; means for determining the position of said blade, said means embodying a rack bar rigidly mounted on said blade, and a spring-actuated latch member adapted for normally engaging the teeth of said rack bar; and means for holding said latch member from engagement with said bar during the movement of said blade.
6. An apparatus as characterized comprising a stick plate having a series of parallel rectangular top-opening, type-holding grooves, said grooves having an entrance guide terminal recess; means for determining the length of lines of composite type, said means embodying a gage blade, and a clamp mounted in said blade for gripping the plate to hold said blade rigid thereon; means for determining the position of said blade, said means embodying a rack bar rigidly mounted on said blade, and a spring-actuated latch member adapted for normally engaging the teeth of said rack bar; and means for holding said latch member from engagement with said bar during the movement of said blade, said means embodying a pressure plate, and shank rigidly connected therewith and with said latch member.

EDWARD HUGO BOOS.
